UNITED STATES PATENT OFFICE.

FRANK M. HILGERT, OF SPOKANE, WASHINGTON.

TROUSERS-SUPPORTER.

966,093.

Specification of Letters Patent. Patented Aug. 2, 1910.

Application filed September 8, 1909. Serial No. 516,649.

To all whom it may concern:

Be it known that I, FRANK M. HILGERT, a citizen of the United States of America, residing at Spokane, in the county of Spokane and State of Washington, have invented new and useful Improvements in Trouser-Supporters, of which the following is a specification.

This invention relates to trousers supporters, and one of the principal objects of the same is to provide a supporter for trousers which shall be of simple construction and which will be practically invisible when in use.

Another object of the invention is to provide a trousers supporter comprising a belt adapted to surround the hips below the waist inside the trousers and to be provided with supporting devices extending up inside the trousers and provided with loops adapted to engage buttons upon the waist band of the trousers upon the outside.

These and other objects may be attained by means of the construction illustrated in the accompanying drawing, in which,—

Figure 1 is a perspective view of a trousers supporter made in accordance with my invention, showing a portion of the waist band of a pair of trousers connected thereto. Fig. 2 is a detail elevation of one of the supporting members showing the belt in section. Fig. 3 is a vertical sectional view taken through the belt and waist band of the trousers. Fig. 4 is a detail perspective view of one of the base plates.

Referring to the drawing, the numeral 1 designates a belt designed to pass around the hips slightly below the waist, said belt having a wire loop 2 secured to one of its ends by means of stitches 3. This loop is provided with a rectangular extending portion 4 forming an eye for the hook member 5. This hook member is formed on the end of the wire loop 6 secured to the opposite end of the belt.

The supporters each comprises a base plate 7 provided with notches 8 at the upper and lower edges thereof and a series of perforations 9 in the body of the plate, said perforations being provided with burs 10 upon the inner side of the plate, as shown in Fig. 3, said burs adapted to engage the belt 1 and to prevent the plate from slipping.

The supporting members comprise the base plate and the upwardly extending parallel arms 11 terminating at their upper ends in a downwardly extending button loop 12. The arms 11 extend downward at the rear side of the belt 1 and at the front are bent upwardly in the form of parallel arms 13, 60 said arms engaging the notches 8 at the top and bottom of the base plate 7 and said arms at their upper ends being extended backward and bent around the arms 11 at 14.

Upon reference to Fig. 1 of the drawing, 65 it will be seen that there is a supporting device for each of the suspender buttons 15 secured to the waist band of a pair of trousers 16, two of said supporters at the back of the belt and four in front.

From the foregoing it will be obvious that the belt 1 being connected below the waist and the supporters extending up underneath the waist band and underneath the buttons 15, as shown in Fig. 1 of the drawing, the 75 trousers will be supported at a proper height and the supporting devices will be practically invisible. The waist belt 1 may be disconnected in front and taken off with the trousers without removing the button loops 80 12 from the buttons 15.

I claim:—

A trousers support comprising a belt having fastening means on its ends, a series of supports mounted on the belt, said supports 85 each comprising a base plate having a series of burs upon the inner side thereof to engage the belt and notches at the top and lower edges thereof, and supporters, said supporters being constructed of a single 90 strand of wire having its upper portion projected above the plate and formed with a downwardly extending button loop, the arms of the supporter adapted to engage one of the faces of the plate and to be bent within 95 the lower notches of the said plate and to have its extremities passed through the upper notches of the plate and connected with the arms.

In testimony whereof I affix my signature 100 in presence of two witnesses.

FRANK M. HILGERT.
